UNITED STATES PATENT OFFICE.

LOUIS B. FULTON, OF PITTSBURG, PENNSYLVANIA.

EJECTOR AND INJECTOR.

SPECIFICATION forming part of Letters Patent No. 280,783, dated July 3, 1883.

Application filed October 31, 1882. (Model.)

To all whom it may concern:

Be it known that I, LOUIS B. FULTON, of Pittsburgh, in the county of Allegheny and State of Pennsylvania, have invented certain 5 new and useful Improvements in Ejectors and Injectors; and I do hereby declare that the following is a full, clear, and exact description of the invention, which will enable others skilled in the art to which it appertains to 10 make and use the same, reference being had to the accompanying drawings, which form a part of this specification, in which—

Figure 1 is a longitudinal section, and Fig. 2 a transverse section, of an ejector with my 15 improvement. Figs. 3 and 4 are longitudinal sections of another form of ejector, showing my improvements; and Fig. 5, a transverse section of same. Figs. 6 and 7 are respectively a longitudinal and transverse section of another 20 form of ejector with my improvements. Fig. 8 is a transverse section of a modification. Fig. 9 is a longitudinal section of another form of 25 ejector with my improvements.

In ejectors and injectors, as generally constructed, either the steam-nozzle or the inner 30 head or combining-tube stands partially or wholly across the line of the induction-opening, and, in consequence, the inflowing current of water or liquid is compelled to part 35 into at least two portions to pass wholly or partially around the steam-nozzle, or around the combining-tube mouth or inner head. In fact, where neither the nozzle nor inner head projects in the way of the inflowing current of 40 water, the momentum of the uncondensed steam acts as though it were a solid body, and the inflowing current splits, part rising on each side, before taking the direction of the axis of the eduction-pipe or combining-tube. I have 45 discovered that from this fact arise two drawbacks to the best possible performance of both ejectors and injectors. The water rising into the siphon-head or injector-body, divides, as stated, and then, before it has fully 50 felt the suction of the steam-jet, the two bodies of water meet, and the result is that part, at least, of its previously acquired velocity is annihilated, so that an additional amount of steam must be wasted in recovering such velocity; hence the steam is not allowed to do all the work it could do if the velocity were

not in this manner destroyed in the head. On the other hand, if, as is nearly always the case, the head of the siphon should be a little out of true, the upgoing body of water will be 55 unequally divided, and the greater portion will preponderate in momentum. The consequence is that the velocity is partly annihilated and the remainder rendered ineffective by the resultant spiral direction thereby given 60 the current through the combining-tube or eduction-pipe, thus again rendering a portion of the steam inefficient in the action of the siphon or injector.

The object of this invention is to prevent 65 this waste of steam, and in doing so add to the efficient power of the device.

The invention accordingly consists, broadly, in providing an ejector or injector with a septum or wall dividing the head in such manner that the body of water or fluid divided by the steam nozzle or jet or by the inner head or combining-tube is not allowed to suffer collision and have its velocity destroyed; further, in the arrangement and combination 75 of devices, as hereinafter fully described and claimed.

In Figs. 1 and 2 of the drawings, A designates the head or shell, B the induction-opening, C the steam branch, and G the combining-tube, all as shown in Letters Patent No. 231,789, granted to me August 31, 1880.

Referring to Fig. 2, it will be readily understood that the current of water rising from opening B becomes parted into two portions, 85 which rise around the mouth of the combining-tube G, and above the latter they meet, and their velocity is at least partly destroyed, with the consequences already stated. I construct the shell A with a radial septum or wall, b, 90 in that part of the shell opposite the induction-opening B, and in line with the axis of the steam jet or jets. This makes the two sides of the shell independent of each other, and independently subject to the influence of the operating 95 steam-jet, and the two bodies of water are not permitted to merge into one stream till they have both assumed a common direction, after which they pass out of the siphon together without the confusion or eddies otherwise consequent upon their merging before having taken 100 the common direction. The result is that the

siphon starts very quickly and its operation is much improved, the twisting of the delivery-column avoided, and for a given steam supply and pressure a greater volume of water can be 5 siphoned than where the septum *b* is absent. These advantages accrue whether the device is used as an injector for lifting or forcing, or both, or as an ejector in any of its many applications. Fig. 3 shows another form of ejector, 10 in which I form the septum *b* in the upper part of the head *H* and between it and the inner head *I*; Fig. 4, the double-acting form of the siphon, Fig. 3, also having the septum *b* passing along so as to insure the separation of the 15 two bodies of water until they have entered the combining-tube *J*. Fig. 5 shows the same in cross-section. Figs. 6 and 7 show another double-acting form of ejector, also having the septum *b* similarly arranged. In all of these 20 forms, whether the ejector is single, double-acting, or triple-acting, the effect of the septum is the same—namely, a total avoidance of the loss of steam caused by the destruction of the velocity of the current of water by reason 25 of back or counter currents, eddies, twists, or whirls, and a resultant increase of efficiency for a given amount and pressure of steam. Any construction which will prevent the direct collision of the two bodies of water in a 30 siphon or injector may be adopted. For instance, in Fig. 8 (a view similar to Fig. 2) I show a partial septum, *b'*, curving gradually, so that while the two currents meet before 35 getting the axial direction they do not collide to reduce the velocity, but run along side by side unimpeded by eddies or whirls.

In Fig. 9, I show an old-style siphon having my improved septum inserted or cast in place, with a resulting operation which is 40 vastly superior to its operation without the septum.

The septum may be formed in casting the shell, or it may be inserted afterward.

The same principles and construction are

also applicable to injectors, whose operation is 45 generically the same as that of ejectors, and need not be specifically described.

I claim as my invention—

1. In an ejector or injector in which the inflowing current is divided by the steam nozzle or jet, inner head, or other device, a septum or wall, *b*, so located, substantially as described, in the head or shell as to prevent the direct collision of the two currents in the head or shell. 55

2. In an ejector or injector of the class described, a septum or deflector, *b*, projecting inwardly from the head or shell at a point about opposite the induction-opening of the shell, substantially as described. 60

3. An ejector or injector having an internal septum or deflector radially arranged in the head in line with the axis of the steam-jet and between it and the shell of the ejector or injector, substantially as described. 65

4. An ejector or injector having on or attached to its shell a septum or deflector radially projecting toward the steam-jet axis, and in line therewith, substantially as described, whereby the two bodies of water in the sides 70 of the shell are prevented from direct collision.

5. In an ejector or injector having an inner head or combining-tube projecting into the shell or outer head, the combination therewith of an internal septum or deflector projecting 75 from the shell toward and to or nearly to the said inner head or combining-tube, in line with the axis thereof, and extending lengthwise over the entire inwardly-projecting portion of said inner head or combining-tube, 80 substantially as described.

In testimony that I claim the foregoing as my own I have hereto affixed my signature in presence of two witnesses.

LOUIS B. FULTON.
